UNITED STATES PATENT OFFICE.

GEORGE W. GRIMM, OF WEST HOBOKEN, NEW JERSEY.

ARTIFICIAL TOOTH.

1,270,943.

Specification of Letters Patent.

Patented July 2, 1918.

Application filed December 31, 1917. Serial No. 209,680.

To all whom it may concern:

Be it known that I, GEORGE W. GRIMM, a citizen of the United States, residing at West Hoboken, in the county of Hudson and State 5 of New Jersey, have invented certain new and useful Improvements in Artificial Teeth, of which the following is a full, clear, and exact specification.

This invention relates to artificial teeth, 10 and one of its objects is to provide an improved porcelain crown tooth with an adjustable attachment for use on vulcanite plate work or other dentures.

Special objects are to facilitate the attachment of an anchoring device to the crown and insure the firm retention of said anchoring device whether it is baked in the crown or afterward attached thereto.

Other objects are to provide an improved 20 means of attachment of the teeth to the plate which permits said plate to be made lighter in weight and less bulky, to give greater comfort to the wearer, to afford more room for the tongue, to promote clearer enunciation by wearers of artificial teeth, to dispense with the use of vulcanite or other backing behind the porcelain crown, thereby improving the color or appearance of the tooth and making it more nearly like a 25 natural tooth, and to permit the tooth to be ground away at the neck portion to fit the gum and conform to the alveolar ridge without weakening the attachment of the tooth to the plate or other denture.

30 A further important object is to make the attachment in separate parts so that the grinding and fitting of the crown to the alveolar ridge may be done before the final attachment is made. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the 50 several views:—

Figure 1 is a central vertical section through a tooth or crown constructed and attached to a plate or denture substantially in accordance with this invention.

Fig. 2 is a section on the line II—II of 55 Fig. 1.

Fig. 3 is a detailed view of the complete anchoring device with its parts detached from each other.

Fig. 4 is a detailed view of a modified 60 form of the top member of the anchoring device anchoring member.

Figs. 5 and 6 are detailed views of modified forms of the bottom anchoring member, and

Fig. 7 is a central vertical section of a porcelain crown showing the bottom member of the anchoring device as it is secured therein after baking.

The porcelain crown or body portion of 70 the artificial tooth 1 is formed with a cavity 2 in its end for connection with the vulcanite plate or other denture 3, as illustrated in Fig. 1. In order to strengthen this connection, the socket or cavity 2 is formed with 75 an inwardly protruding ridge 4 intermediate its base and upper edge, and the walls of the cavity above and below said ridge are concave, as at 5 and 6. The diameter at the innermost edge of the ridge 4 is less than the 80 greatest diameter of the concave portion 5 below said ridge. The connection between the crown and plate is strengthened or reinforced by a metal anchoring device comprising a bottom member 7, a top member 85 8 and a connecting member or pin 9. The crown 1 is bored at the bottom of the cavity 2 to receive the bottom member 7 which may be baked therein, as illustrated in Fig. 1, or secured therein after baking, as illustrated 90 in Fig. 7.

Said member 7 is formed with a screw threaded socket 10 to receive the lower screw-threaded end 11 of the pin 9. The upper end of said pin is also threaded at 12 95 preferably in the opposite direction, to engage a threaded passage 13 in the member 8. The member 7 is fixed at the base of the bore 14 in the crown, while the member 8, when in position as shown in Fig. 1, seats 100 upon the upper edge of said bore at the bottom of the cavity 2, being retained in that position by the pin 9 having its screw threaded ends 11 and 12 engaging the socket 10 in the member 7 and the passage 13 of the 105 member 8, respectively.

The bottom member 7 of the anchoring device is preferably formed with a conical

lower end 15 and an annular groove 16, as shown in Figs. 1 and 2, in order to strengthen the joint between it and the crown. Other forms of the bottom anchoring member may, however, be used as, for instance, with the straight sides illustrated at 17, Fig. 5, or with bulged sides 18, Fig. 6. The top member and pin may also be made in one piece, if desired, as illustrated at 19, Fig. 4. The top member 8 of the anchoring device preferably has its lower face rounded or inclined, as at 20, to permit the vulcanite to flow in around said head and thus strengthen the connection. Said member 8 is further provided with notches 21 to receive a spanner wrench for adjusting the same and also for preventing said member from becoming unscrewed or loose after the vulcanite has set around it.

When the anchoring device is to be attached to the crown after the latter has been baked, the walls of the bore 14 are preferably made divergent near the bottom of said bore, as illustrated at 22 in Fig. 7, so that the cement or other filling material 23 used for securing the member 7 fills this enlarged bottom portion of the bore in the crown as well as the groove 16 in the member 7, thereby making a very strong joint. The top of the member 8 is arranged below the ridge 4 in the cavity 2, so that the plastic material or vulcanite which fills the portion of the cavity below said ridge is held firmly around said member.

The bottom member 7 of the anchoring device, if attached to the crown before baking, will not interfere with said crown being ground to fit the gum and uneven surfaces of the alveolar ridge, whereas, if the entire anchoring device were made in one piece with its top end projecting from the bore 14, it would be in the way of the grinding disk or tool generally used for grinding down and fitting crowns. If necessary, the upper portion of the crown may be ground down as far as the broken lines X—X or Y—Y on Figs. 1 and 7, respec-

tively, without affecting the use of the anchoring device, it being only necessary in such case to shorten the pin 9.

Having thus described my invention, what I claim as new and desire to secure by Letters Patent of the United States is:—

1. In an artificial tooth, the combination with a crown having a cavity therein, of an anchoring device comprising a bottom member secured in said cavity and having a screw-threaded socket in its upper end, a top member adapted to be embedded in the plastic material to which the crown is to be attached, said top member having a screw threaded passage, and a connecting pin having threads on its ends to engage the threaded socket in the bottom member and the passage in the top member, respectively.

2. In an artificial tooth, the combination with a crown having a cavity therein, of an anchoring device comprising a bottom member secured in said cavity and having a screw-threaded socket in its upper end, a top member adapted to be embedded in the plastic material to which the crown is to be attached, said top member having a screw threaded passage, and a connecting pin having oppositely inclined threads on its ends to engage the threaded socket in the bottom member and the passage in the top member, respectively.

3. In an artificial tooth, the combination with a crown having a bore therein with diverging walls, of an anchoring device comprising a bottom member arranged between the diverging walls of the bore, and a headed member connected to said bottom member and adapted to be embedded in plastic material to which the crown is to be attached, and a plastic filling around said bottom member within the diverging walls of the bore for securing said bottom member in place said bottom member having an annular groove also occupied by said plastic filling.

In testimony whereof I have signed my name to this specification.

GEORGE W. GRIMM.
